UNITED STATES PATENT OFFICE.

FRANK O. ERICKSON, OF ST. LOUIS, MISSOURI.

HAT-FORMING DIES.

Application filed September 20, 1928. Serial No. 307,317.

This invention relates to dies used for forming and pressing hat blanks in particular shapes.

Heretofore hats have been pressed between metal stamping dies but because of the unevenness of the metal it has been impossible to apply an even pressure to the entire surface of the hat, with the result that the hat shape produced was not evenly pressed or finished and in some places the unevenness was very apparent and impaired the appearance of the product.

The general object of the present invention is to provide an elastic rubber form carried by one of the dies and hydraulically forced outward against the other die by water pressure to thereby secure an evenly distributed pressure against the entire hat shape, with the result of producing an evenly pressed hat.

A further object is to provide a construction which will press hat shapes of various thicknesses for the reason that the elastic rubber form and the water space between it and the supporting die allows a variation in the space between the inner die and the form, whereas where two metal dies are used only a hat of the thickness of the space between the two dies can be so pressed and new dies are required where hats of various thicknesses are to be pressed.

A still further object is to provide a device of this character which is so constructed that the steam or water vapor developed within the water space or water chamber by the heat of the outside die may be released, thus preventing any bulging in the rubber caused by the collection of this steam or vapor.

Another object is to provide means whereby any excessive steam pressure may be automatically relieved, thus preventing explosions.

Other objects will appear in the course of the following description.

My invention is illustrated in the accompanying drawings, wherein:—

Figure 1 is a vertical sectional view through a hat forming die constructed in accordance with my invention;

Figure 2 is a side elevation thereof;

Figure 3 is a fragmentary sectional view on the same plane as Figure 1 but showing the valve raised.

Referring to these drawings, 10 designates

the base of the die, which may be of any suitable construction, and 11 designates the inner die which is mounted upon this base and is provided with a plurality of openings 12 leading from the interior of the die to the exterior thereof. The base is provided with seats 13 upon which the marginal edge of the inner die 11 fits and the inner die is formed with the outwardly projecting flange 14 which is equal in width to the width of this seat 13. Coating with the inner die is an outer die 15 which has the same general shape as the inner die but is larger than this inner die.

Disposed in spaced relation to the inner die 11 and having its margin resting against the outer face of the seat 13 is an elastic rubber form, designated 16. This rubber form is formed of relatively thick rubber and conforms in general shape to the form of the dies 11 and 15, but it is supported in spaced relation to the die 11. This rubber form carries at its apex or upper end an integral valve 17 and the inner form or die 11 is formed with a valve seat 18 at its apex in which this valve 17 is adapted to fit.

Extending downward from a central opening 19 in the inner die is a tube 20 which opens into said seat 18. The lower end of this tube extends through the base 10 and operating through the tube is a valve stem 21 which engages the valve 17. The lower end of this valve stem 21 rests upon a valve spring 22 which acts to urge the valve stem upward. The outer surface of the valve 17 is provided with a lug 23 and the outer die 15 at its apex is provided with a recess 24 to receive this lug. It will be understood, however, that the lug and recess may be omitted.

For the purpose of holding the rubber form 16 in place, I provide a retaining ring 25 which extends around and confronts the seat 13, this ring being angular in cross section and being held in place by the screws 26. These screws hold this binding ring 25 down tightly against the base and clamp against the projecting margin of the rubber form 16. It will be seen that the rubber form 16 is held in spaced relation to the inner die 11 so that a water space 27 is provided between the inner die and the rubber form. This water space communicates through the openings 12 with the interior of the inner die and water is supplied to the interior of the inner die under

pressure by means of the water inlet pipe 28. The top die is provided with the usual clutch bar 29. I have not illustrated the means whereby the top die is supported and forced down onto the lower die, as this forms no part of my invention and such means is old and well known.

In the use of this invention, water is forced into the inside of the inner die through the pipe 28 and into the water space between the outside surface of the inner die and the elastic covering or form. The valve 17 of the inner die permits air, steam or gas to escape while the water is flowing into the die and the water space. The valve is adjusted by means of the valve stem and the spring forces this valve upward when the pressure applied by the outside or upper die is released. Thus this valve works automatically. This valve is so adjusted that when no pressure is applied to the outside die, the valve is opened, permitting air, gas and steam to escape, but when the water space is filled with water and the outside die lowers, this valve closes so that the entire water space on the inside of the inner die is completely filled to capacity with water. Hydraulic pressure is then applied to the water and the elastic covering on the inside of the outer die is forced outward by the hydraulic pressure and presses against the hat shape which is fitted over the elastic covering and the hat is pressed into the desired shape between this elastic covering and the inside of the outer die.

The advantage of this construction is that the hydraulic pressure applied to the inside face of the elastic rubber form secures an evenly distributed pressure against the hat shape and the result is an evenly pressed hat.

An evenly pressed hat is not possible where metal dies are used because of the unevenness of the metal, it being practically impossible to secure an absolutely parallel surface throughout the entire confronting surfaces of the pair of dies. The result is that the hat shape produced is not evenly pressed or finished and sometimes this unevenness is very apparent and impairs the appearance of the product. This is entirely eliminated by my construction.

Another advantage of this construction is that it will press hat shapes of various thicknesses because the elastic rubber form and the water space allows for variation in the space between the inner die and the elastic rubber form, whereas where metal dies are used only hats of a predetermined thickness can be pressed and new dies are required where hats of various thicknesses are to be pressed. In the process of pressing a hat shape by means of this device, it is necessary to heat the outside or top die and the heat from this top die or outside die causes steam to develop within the water space or water chamber. If the pressure of this steam is not relieved, a bulge in

the rubber will be caused, and this relief of the steam is secured by the automatic valve 17 above referred to. This will prevent any undue bulging of the rubber form and at the same time serves as a safety valve and prevents explosions caused by the expansion of the steam.

It will be understood, of course, that the inner die and the outer die may have any desired form and that I do not wish to be limited to the form illustrated as this form or shape will depend entirely upon the character of the hats being pressed. Neither do I wish to be limited to the details of construction as these might be modified in many ways without departing from the spirit of the invention as defined in the appended claims.

I claim:

1. A hat forming means comprising inner and outer dies, an elastic covering or form having water-tight engagement at its margin with the inner die but separate therefrom, the inner die having openings leading from the interior of the inner die to the space between it and the elastic covering, and means for forcing fluid under pressure into the interior of the inner die and thus into the space between the inner die and the elastic covering or form.

2. A hat forming means comprising an inner die and an outer die, an elastic covering or form fitting over the inner die but separate therefrom, means for holding this form in fluid-tight contact with the base of the inner die, and means for forcing fluid under pressure into the space between the inner die and said elastic form.

3. A hat forming means comprising an inner die and an outer die, an elastic covering or form fitting over the inner die but separate therefrom, means for holding this form in fluid-tight contact with the base of the inner die, means for forcing fluid under pressure into the space between the inner die and said elastic form, and means for automatically relieving excess pressure between the inner die and said form.

4. A hat forming means comprising an inner die and an outer die fitting over the inner die, a base upon which the inner die is mounted and upon which the outer die is adapted to rest at its margin, the inner die being hollow and provided with a plurality of openings leading to the outer face thereof, an elastic covering or form fitting over the inner die but separate therefrom and having water-tight engagement with the base, and means for forcing water under pressure into the interior of the inner die and so into the space between the inner die and the elastic form to thus force the elastic form out against the outer die.

5. A hat forming means comprising a base having a die seat, a hollow inner die mounted upon said base and having its margin rest-

ing against said seat, an elastic covering or form fitting loosely over the inner die but separate therefrom and having its margin extending downward over the outer edge of 5 said seat, a clamping ring holding the margin of the form in place against the seat, an outer die larger than but conforming in general shape to the inner die and adapted to fit over said rubber covering, and means for 10 forcing water under pressure into the space between the inner die and said elastic covering.

6. A hat forming means comprising a base having a die seat, a hollow inner die mounted 15 upon said base and having its margin resting against said seat, an elastic covering or form fitting loosely over the inner die but separate therefrom and having its margin extending downward over the outer edge of said seat, 20 a clamping ring holding the margin of the form in place against the seat, an outer die larger than but conforming in general shape to the inner die and adapted to fit over said rubber covering, means for forcing water under 25 pressure into the space between the inner die and said elastic covering including a plurality of openings extending through the inner die to the outer face thereof, and a water inlet extending through said base into the 30 interior of the inner die and connected to a source of water under pressure.

7. A hat forming means comprising a base having a die seat, a hollow inner die mounted upon said seat and having its margin resting 35 against said seat, an elastic covering or form fitting loosely over the inner die but separate therefrom and having its margin extending downward over the outer edge of said seat, a clamping ring holding the margin of the 40 form in place against the seat, an outer die larger than but conforming in general shape to the inner die and adapted to fit over said rubber covering, means for forcing water under pressure into the space between the 45 inner die and said elastic covering including a plurality of openings extending through the inner die to the outer face thereof, and a water inlet extending through said base into the 50 interior of the inner die and connected to a source of water under pressure, the inner die being formed with an air and steam outlet extending through the base and

with a valve whereby excess pressure may be relieved.

8. A hat forming means comprising a base 55 having a die seat, a hollow inner die mounted upon said base and having its margin resting against said seat, an elastic covering or form fitting loosely over the inner die but separate therefrom and having its margin extending 60 downward over the outer edge of said seat, a clamping ring holding the margin of the form in place against the seat, an outer die larger than but conforming in general shape 65 to the inner die and adapted to fit over said rubber covering, means for forcing water under pressure into the space between the inner die and said elastic covering including a plurality of openings extending through the inner die to the outer face thereof, and a water inlet extending through said base into the 70 interior of the inner die and connected to a source of water under pressure, the inner die being formed with an air and steam outlet extending through the base, the elastic 75 covering being formed with a valve normally seating in said air outlet and preventing the escape of vapor therefrom when the outer die is in place but being urged away from the outlet when the outer die is out of contact with the elastic form.

9. A hat forming mechanism of the character described comprising a base, an inner die seated upon the base, a rubber covering or form extending over the outside surface 85 of the inner die but separated therefrom, an outer die adapted to fit over the rubber covering, the inner die being provided with an air outlet pipe extending through the base and with a valve seat at the apex of the inner die, an opening in the said air outlet, the form being provided with a valve normally seating in said seat when the outer die is 90 pressed toward the rubber covering, a valve stem engaging said valve and extending down through the air outlet passage, a spring urging the valve stem upward and the valve from its seat, and means for forcing liquid under pressure into the space between the inner die and the rubber covering or form.

In testimony whereof I hereunto affix my signature.

FRANK O. ERICKSON.
